AUTOMOBILE RADIO AND COMMUNICATION SYSTEM

Alfred N. Goldsmith, New York, N. Y., assignor
to Radio Corporation of America, a corpora-
tion of Delaware

Application December 9, 1935, Serial No. 53,529

8 Claims. (Cl. 179—2)

My present invention is concerned with a system wherein an automobile radio receiver or receivers are used not only for radio reception but, in conjunction with certain additional equipment, for intra-car communication between the 5 occupants of the back of the car and the occupants in the front of the car (for example, the chauffeur). The system of communication may be one-way or two-way as more specifically set forth hereunder.

Automobile radio receivers are generally located at this time in the front of the automobile, their loud speakers being associated with them or closely adjacent thereto. It is known, however, that automobile receivers may be located in the back of the car, and alternatively or in addition, that extension loud speakers may be placed in both the front or back of the car, operated from a single receiver, thus enabling all occupants of 20 the car to hear the signals more clearly above incidental noises. It is also a fact that the glass or other partition between the front and back of a number of closed cars makes communication between persons in the back of the car and the 25 chauffeur, for example, difficult in the absence of a special communication system having loud speaking characteristics. There are occasions when a caution or a direction to the chauffeur should be promptly and clearly given. My 30 invention is particularly directed toward securing effective communications between the front and back of the car, regardless of intervening partitions and incidental noises, and through the utilization of available circuit elements and loud 35 speakers of one or more radio receivers located in the automotive vehicle.

My invention comprises essentially the following elements: An assembled radio receiver, (usually in an automotive vehicle), including the 40 power supply, amplifier, and loud speaker thereof; one or more microphones located out of earshot of the receiver in general; and switching means whereby the output of the said microphone may be amplified by the audio-frequency 45 amplifier of the said radio receiver and the resulting output made audible through the radio-receiver loud speaker.

It is a particular feature of my invention that the person controlling the switching means at 50 the remote microphone can (a) supersede the control of the radio-receiver audio frequency output through the incoming radio signal, by the output of the remotely-located microphone, and (b) supersede the on-or-off control of the radio receiver as a whole by means of the remotely lo-

cated switch. That is, if the receiver is off, the remote switch enables it to be turned on; when the remote switch is restored to the "off" position, the radio receiver is then itself turned off. However, if the radio receiver is on when the operator of the remotely located switch desires to take control of the radio receiver output by means of his microphone, he can do so but his switch does not either turn on or off the remote radio receiver.

The novel features characteristic of my invention are set forth with particularity in the appended claims. The invention itself, however, both as to its construction and mode of operation together with the objects and advantages 15 thereof, will best be understood by reference to the following description taken in connection with the accompanying drawings in which,

Fig. 1 is a schematic circuit diagram of a suitable radio receiver that may be used in conjunction with my invention. Fig. 2 is a schematic and block diagram of my invention applied to a single receiver in the front of an automobile and communication from the back of the car to the front only. Fig. 3 is a block diagram and schematic circuit showing my invention applied to a two-way communication system between the front and the back of an automobile with a receiver located in each portion of the automobile, and Fig. 4 is a block diagram and schematic circuit 30 of my invention applied to two-way communication between the front and back of the automobile, but with only one receiver, which, for illustration, is placed in the back of the car but could equally well be placed instead in the front. 35

Referring now to Fig. 1 the receiver circuit there shown comprises a radio frequency amplifier 6, a detector 7, an audio frequency amplifier 8 and a second audio frequency or power amplifier 9. It will of course be understood that any 40 other known type of receiver, such as the super-heterodyne, may be employed. A suitable loud-speaker 10 is energized from the power amplifier 9. The power supply 11, of which the automobile storage battery A is a part, is utilized to supply plate potential, grid bias and filament current to the several stages in the conventional manner. The detector stage may be of the grid-leak and condenser type or of the grid bias or power type and is provided in its input with a 45 pair of terminals 1—2 and a third terminal 3. It will of course be understood by those versed in the art that the terminals 1—2—3 may equally well appear in the input circuit of the audio frequency amplifier. A switch 12 is connected in

the power supply circuit between the terminals 4—5 and serves as the on-off switch for the radio receiver. If an audio frequency input is desired to be amplified by tubes 7 and/or 8 and 9, it 5 may be injected between terminals 1 and 2 in the input of detector 7, or alternatively between similar terminals in the input of amplifier 8 (not shown). If terminals 1 and 3 are short-circuited no radio reception is possible. If 4 is connected 10 to 5, the receiver is operative; if the power supply circuit is opened at 4—5 the receiver becomes inoperative.

The radio frequency portion of the receiver 15 may be rendered ineffective by means other than above described. For example, this portion may be open-circuited as by opening the connection between terminals 1 and 2, and by injecting the audio frequency input between terminals 2 and 3. Or else the radio frequency portion may be markedly de-tuned from any signal reception position as by introducing resistances in the tuned 20 circuits or shunting the tuning condensers or their trimmers or both. Alternatively said portion may be desensitized, as for example, by the usual volume control methods as by varying the grid bias. Alternatively said portion may be rendered ineffective by disconnecting the filament current or the plate voltage or both, for the tubes contained 25 within said radio frequency portion.

30 In Fig. 2, B represents the back of the car and F the front of the car, the partition being indicated by the vertical dot and dash line. 20 represents the receiver of Fig. 1 as a block. 21 is a microphone which, through battery 22 and transformer primary 23, may produce speech voltages across the terminals of the transformer secondary 24. 25 is a push button or other switch. When depressed, current from battery 28 energizes the electromagnetic relay 26 which operates 35 the 5-pole double-throw switching mechanism 27. The center row of contacts of the switch mechanism are connected permanently to the receiver as indicated by the dotted lines; the first contact to one terminal of primary 23; the second and fourth contacts are connected together and to terminal 1 of the receiver; the third contact to terminal 2 of the receiver, and the fifth contact to terminal 4 of the receiver power supply. When coil 26 is energized, the switch is thrown 40 in the transmit direction T. Thus the microphone circuit is closed, the output of secondary 24 is connected through the switch contacts to terminals 1—2, 1 is short-circuited to 3, and 4—5 is closed thereby turning on the radio receiver regardless of whether it has been previously in use 45 in the front of the car or not. If switch 25 is released the switch 27 is thrown in the receive direction R. The receiver is turned off unless it is already turned on by the occupant of the front 50 of the car) and terminals 1—2 are connected together to complete the detector input circuit enabling satisfactory radio reception.

To talk to the front of the car an occupant of the back presses switch 25 and talks. When he 55 has completed his speech he releases switch 25 thus permitting radio reception in the front of the car if desired. The batteries 22 and 28, it will be understood, may be the car battery A and are shown here separate only for convenience in 60 circuit delineation. Similarly, the wiring between B and F is not all necessary because one side of the car battery may be grounded to the frame of the car thus enabling a return circuit through the frame of the car if so desired. This will diminish the number of conductors required 65

in the system between the front and back of the car. If desired the switching mechanism 27 and its associated apparatus may also be located in the back of the car.

Fig. 3 illustrates a two-way communication system according to my invention and includes a pair of circuits identical to that shown in Fig. 2. The circuit comprising the microphone 21, microphone switch 25, relay 26, switching mechanism 27 and receiver 20 provides communication from the back of the car B to the front F, as in Fig. 2, whereas the circuit comprising the microphone 31, microphone switch 35, relay 36, switching mechanism 37 and receiver 30 provides communication from the front of the car F to the back B. Instead of showing the batteries their positive and negative terminals only are indicated. Resistances 29 and 39 are stabilizing resistances for preventing either microphone 21 or 31 from drawing an excessive current when placed substantially in parallel with the other during two-way communication, thereby preventing equally effective communication in both directions.

Fig. 4 is similar to Fig. 3 except that only one radio receiver 40 is provided, and in this case in the back of the car (although the single receiver in question might equally well be placed in the front if desired). Fig. 4 differs from Fig. 3 primarily in that the loud speakers 48 and 58 have a special connection across their terminals as shown. The loudspeaker 48 is that contained in the radio receiver 40, and the second loud speaker 58 placed in the front of the car is connected in parallel therewith through the switch 53. In the reception of radio programs, that is with the switch mechanism 47 in the receive position R, the occupants of both the rear and the front will hear the programs through loudspeakers 48 and 58, respectively, unless the chauffeur, for example, opens the switch 53 when radio reception in the front only will be discontinued.

Communication between the front and the rear of the car will be established by manipulation of either push button switch 45 or 55 as explained in connection with Figs. 2 and 3. In each instance the relay 46 will be energized to throw the switch 47 to the transmit position T. In order to avoid the possibility of the chauffeur or other occupant in the front of the car not hearing instructions spoken into the microphone 41, should the switch 53 be in its open position at the moment, the switch mechanism 47 is provided with a pair of contacts 42—52 which have leads connected to the terminals of switch 53, said contacts being connected together in the transmit position of switch 47, thereby completing the circuit of loudspeaker 58 whether switch 53 is open or closed. The stabilizing resistances 49, 59 serve the same function as resistances 29, 39 in Fig. 3.

I desire not to be restricted to pleasure automobile installations but regard my invention as applying equally to automobile trucks, trailers, buses, passenger trains, freight trains, and air craft as well as motor boats, yachts, and larger marine crafts. The application to automobiles is illustrative. In the case of passenger trains, for example, the separation between the points enjoying communication with each other may be considerable and far in excess of that of an automobile.

What I claim is:

1. In combination, a radio receiver having a radio frequency portion and an audio frequency portion, a single power supply source, a local switch associated therewith for energizing and

deenergizing said both portions of the receiver, a remote source of audio frequency signals, a first remotely controlled means for energizing the receiver irrespective of the position of the local switch, a second remotely controlled means for rendering ineffective the radio frequency portion, and a third remotely controlled means for impressing the remote signal source on the audio frequency portion of the receiver.

10 2. The invention according to claim 1 wherein a single means is employed to simultaneously actuate the several remotely controlled means.

15 3. In combination, a radio receiver having a radio frequency portion and an audio frequency portion, a local switch for energizing and deenergizing both said portions of the receiver, a remote microphone source of speech currents and a circuit therefor, switch mechanism associated with both the receiver and the microphone circuit, said switch mechanism being normally in position to open-circuit the microphone circuit and to complete the receiver circuit, and remotely controlled means for actuating said switch mechanism from its normal position to 20 simultaneously energize the receiver irrespective of the position of the local switch, render ineffective the radio frequency portion, close the microphone circuit and impress the speech currents from said microphone circuit onto the audio frequency portion of the receiver.

25 4. In combination, a radio telephone receiver and loud speaker permanently associated therewith, a remote loud speaker actuated by the signals from the receiver, means for silencing the radio signals at the remote loud speaker, a microphone in the vicinity of the receiver, means for actuating by the speech currents from the microphone in the vicinity of the receiver, the audio frequency portion of the receiver together with the receiver loud speaker and compulsarily as well 30 the remote loud speaker irrespective of the position of the means for silencing radio signals conducted to such loud speaker, a microphone in the vicinity of the remote loud speaker, means for actuating the audio frequency portion of the receiver and the receiver loud speaker by speech currents from the remote microphone, remotely controlled means for energizing said receiver, remotely controlled means for silencing the receiver radio signals, and remotely controlled means for 35 restoring the audio frequency portion of the receiver and the receiver loud speaker to the reception of radio signals.

50 5. A system providing two-way communication

between two suitably spaced points in a vehicle, such as an automobile, comprising a radio receiver located at each of said points, said receivers each including a radio frequency amplifier, detector and audio frequency amplifier, a 5 microphone and control means at each point, and means operative by either of said control means to energize the receiver located at the point distant from the operated control means and to simultaneously connect the audio frequency portion of said distant receiver to the microphone located at the point where the control means is operated.

10 6. A system providing two-way communication between two suitably spaced points in a vehicle, such as an automobile, comprising a microphone located at each of said points, a single radio receiver including a radio frequency amplifier, detector and audio frequency amplifier, control means at each point, and common 15 means operative by said control means at each point to energize the receiver, to render ineffective the radio frequency amplifier portion and to simultaneously connect both microphones to the audio frequency portion of the receiver. 25

15 7. A system according to claim 6 wherein the receiver is provided with a loud speaker at one point for the reproduction of speech currents produced by the microphone located at the other point, a second loud speaker located at said other point also connected to said receiver for the reproduction of speech currents from its distantly located microphone, local means at said other point for rendering said second loud speaker inoperative, and remotely controlled means for 30 rendering said second loud speaker operative from an inoperative condition. 35

20 8. A radio receiver located at a central point, an "on-off" switch for said receiver at a remote point, a microphone source of speech currents 40 at the remote point, a control key at the remote point, and automatic control mechanism operative in response to the actuation of said control key for effecting the following operations at the will of the operator: (1) actuating the "on-off" 45 switch to energize or deenergize the receiver, (2) to permit normal operation of the radio receiver, and (3) to render ineffective only the radio frequency portion of the receiver and simultaneously therewith to effect transmission of the 50 microphone speech currents from the audio frequency portion of the receiver.

ALFRED N. GOLDSMITH.
